Primary Examiner — Rhea Shields

(74) Attorney, Agent, or Firm — Barnes & Thornburg LLP

(57) **CLAIM**

The ornamental design for a junction box for data conductors, as shown and described.

DESCRIPTION

2.1 is a perspective view;

2.2 is a front view;

2.3 is a rear view;

2.4 is a top view;

2.5 is a bottom view;

2.6 is a right side view; and

2.7 is a left side view.

The broken lines depict portions of the junction box for data conductors that form no part of the claimed design.

1 Claim, 7 Drawing Sheets(56)
